J. SCHNABEL

SCOOP BOARD LATCH

Filed Nov. 28, 1925

UNITED STATES PATENT OFFICE.

JOHN SCHNABEL, OF HAMPTON, IOWA.

SCOOP-BOARD LATCH.

Application filed November 28, 1925. Serial No. 71,948.

This invention relates to land vehicles and pertains particularly to a wagon scoop board.

The primary object of this invention is the provision, in a manner as hereinafter set forth, of a means for securing a scoop board in position against the end of a wagon body to make the board grain tight.

Another object of the invention is the provision, in a manner as hereinafter set forth, 10 of a scoop board provided with side wings adapted to overlie the sides of a wagon body to facilitate the loading of grain into the wagon and having means whereby the scoop board may be secured in any desired outwardly inclined position from the end of 15 the wagon body.

A further and final object of the invention is the provision, in a manner as herein-after set forth, of a scoop board and latch 20 structure of simple but strong and durable construction, easy to manipulate, inexpensive to manufacture and adapted to be easily and quickly placed into position.

The invention will be best understood 25 from a consideration of the following detailed description taken in connection with the accompanying drawing forming a part of this specification, with the understanding that the invention is not confined to any 30 strict conformity with the showing of the drawing but may be changed and modified so long as such changes and modifications mark no material departure from the salient features of the invention as expressed in the 35 appended claims.

In the drawing:—

Figure 1 shows in side elevation a portion 40 of the rear of a wagon body showing the scoop board and latch structure embodying this invention applied thereto.

Figure 2 is a top plan view of the same.

Figure 3 is a vertical section taken upon the line 3—3 of Figure 1.

Referring now to the drawing in detail 45 wherein like numerals of reference indicate corresponding parts throughout the several views, the numeral 1 indicates the bottom of a wagon body which is provided with the usual side boards 2.

In order to make such wagon bodies suitable for the carrying of grain, the sides are built up to give a body of greater depth and this building up consists in placing intermediate and upper boards 3 and 4 respectively in edge to edge relation above the side boards 2 as shown. The side boards 2 and

the intermediate boards 3 are provided with the loops 5 and the intermediate boards and the upper boards 4 are each provided with cleats 6 which are designed to extend downwardly through the loops 5 in the boards therebeneath as is clearly shown in Figure 1. In this manner the side boards 3 and 4 are securely held in position over the side boards 2 thus giving a wagon body of greater depth 65 than usual.

Secured transversely of the rear edge of the bottom 1 of the wagon is a series of hinge rod bearings 7 through which a hinge rod 8 extends. Pivotal mounted upon this 70 hinge rod 8 is a grain scoop board or end gate 9 across the rear face of which there extends the reinforcing bands 10, the lower ends of which are looped to receive the hinge rod 8 and thus hold the grain scoop hingedly 75 in connection with the end of the wagon body. This grain scoop, is as shown, of the same height as the built up wagon body and is designed to swing upwardly and fit against the ends of the side boards 2, 3 and 4. 80

At each side of the grain scoop 9 there is secured a retaining wing 11 which extends rearwardly from the grain scoop as shown and which is of greater width at the lower portion than at the upper portion, the upper 85 part tapering inwardly as shown. The lower portion of each of the wings 11, is provided with an arcuate slot 12 through which a bolt 13 extends, which bolt extends from the side of the wagon body 2. Upon the end of 90 this extended bolt, a wing nut 14 is threaded which as shown, may be tightened against the wings 11 to secure the same against the wagon body to thus hold the scoop board in any desired outwardly inclined position. 95

Secured to the outer side of each of the upper side boards 4, inwardly of the end thereof is a latch plate indicated generally by the numeral 15. This latch plate as shown has that edge farthest removed from 100 the rear of the guide board 4, of arcuate contour as indicated at 16, the curve extending from the upper portion of the plate downwardly toward the rear edge thereof. The upper part of the plate at the front edge 105 thereof is split downwardly as indicated at 17 to set up the tongue portion 18 which is bent inwardly beyond the inner face of the plate and, the lower rear edge of the plate is further provided with a rearwardly extending tongue 19 which is also bent inwardly 110 like the tongue 18. These tongues are adapt-

ed to be placed against the side of the boards 4 and have securing bolts 20 passed therethrough, to hold the plate in spaced relation to the outer side of the board.

- 5 Secured to each side edge of the grain chute 9 is a right angled member having a short leg 21 which is secured across the rear side of the scoop board and a relatively long leg 22 which when the scoop board is in up position as shown in Figure 1 lies along side of the top boards 4 and is extended between the side board and the plate 15.

This long leg 22 of each of the right angled members carries a latch arm 23, one end of which is inset and pivotally secured to the leg 22 as at 24 while the other end extends a substantial distance beyond the end of the leg 22 and is formed to provide the handle 25. Each latch arm carries an inwardly extending pin 26 upon the inner face thereof which pin, when the scoop board is in up position with the leg 22 extended beneath the plate 15, rides down over the curved edge 16 of the plate to draw the scoop board 9 tightly against the ends of the side boards of the wagon body. The pin seats in the angle formed between the lowermost portion of the curved edge 16 and the top of the rearwardly extending tongue 19, as shown in Figure 1.

From the foregoing description it will be readily seen that when the scoop board 9 is swung upwardly against the ends of the side boards of the wagon body, the legs 22 of the right angled member carried on each side of the scoop board will pass beneath the latch plate 15 and will act to prevent any side movement of the wagon side boards either inwardly or outwardly thus greatly strengthening the sides of the body. By swinging downwardly the latch arm 23 to cause the pin 26 to ride down over the curved rear edge 16 of the plate 15 a binding, locking action is set up to hold the scoop board tightly against the rear ends of the wagon body side boards, thus preventing any chance of the joint between the scoop board and the wagon body side boards opening to let the grain leak from the wagon.

50 When the scoop board is released and swung outwardly and downwardly as indicated in dotted lines in Figure 1 and in Figure 2, the side wings 11 upon the scoop board prevent the grain from flowing over the sides thereof while being removed or placed into the wagon body.

Having thus described my invention what I claim is:—

1. In a device of the character set forth, including a wagon body, a scoop board hingedly secured to the rear of said body to close the same, a latch plate secured in spaced relation to each side of said body adjacent the rear thereof, said plate having a downwardly curving forward edge, angle shaped members secured one on each side of said scoop board and having one leg adapted to extend between a plate and the body when the board is in closed position, a latch arm pivotally secured to each of said legs, and a pin carried by each arm to ride over said curved plate edge to draw said scoop board tightly to position.

2. In a device of the character set forth, including a wagon body having a scoop board secured to the back thereof to close the same, a keeper element upon each side of the body, each comprising a plate member having portions thereof offset from one face and adapted to secure the plate in spaced relation to the body, the forward edge of each plate being of arcuate contour, a fixed member upon each side of said board adapted to extend beneath an adjacent plate when the board is in closed position, a latch pivotally mounted upon each fixed member adapted to be swung over the outer face of said adjacent plate, and a pin extending from the inner face of each latch and adapted to ride over said arcuate edge to draw said board tightly to position.

3. In a device of the character set forth, including a wagon body having a scoop board secured to the back thereof to close the same, a keeper element upon each side of the body, each comprising a plate member having portions thereof offset from one face and adapted to secure the plate in spaced relation to the body, the forward edge of each plate being of arcuate contour, a fixed member upon each side of said board adapted to extend beneath an adjacent plate when the board is in closed position, a latch pivotally mounted upon each fixed member adapted to be swung over the outer face of said adjacent plate, and a pin extending from the inner face of each latch and adapted to ride over said arcuate edge to draw said board tightly to position, one of said offset portions extending from the lower part of said arcuate edge and acting as a stop for said latch pin.

In testimony whereof, I affix my signature hereto.

JOHN SCHNABEL.
